Filed June 17, 1974, Ser. No. 480,049

Term of patent 14 years

Int. Cl. D28—03

U.S. Cl. D86—10 E

FIG. 1 is a perspective view of the front and left end of a steam curling iron showing my new design;

FIG. 2 is an elevational view of the front of the steam curling iron;

FIG. 3 is a top plan view of the steam curling iron of FIG. 1;

FIG. 4 is a bottom plan view of the steam curling iron;

FIG. 5 is an elevational view of the rear of the steam curling iron;

FIG. 6 is a left end view of the steam curling iron appearing in FIG. 1; and

FIG. 7 is a right end view of the steam curling iron as seen in FIG. 1.

The conventional power cord is shown fragmentarily for ease of illustration.

I claim:

The ornamental design for a steam curling iron, substantially as shown and described.
